UNITED STATES PATENT OFFICE.

LOUIS A. WIMCOVSKY, OF NEW YORK, N. Y., ASSESSOR, BY MESNE ASSIGNMENTS,
TO SUN TYPEWRITER COMPANY, OF NEW YORK, N. Y., A CORPORATION OF NEW
JERSEY.

TYPEWRITING MACHINE.

Application filed July 15, 1924. Serial No. 726,063.

My present invention relates to typewriting machines and in its more specific application to machines of the type designated as portable.

5 The present application is for divisible subject matter disclosed in my two Patents No. 1,504,198 and No. 1,504,199, both dated August 5, 1924.

According to a feature of the invention, 10 the parts of the typewriting machine are assembled in a particularly compact relation to confine the outside dimensions of the machine within minimum proportions. In the preferred embodiment, the universal 15 bar is actuated by the type bars and is assembled to the segment plate and has an open structure to afford space for accommodating the escapement pinion and associated devices which are mounted on the 20 movable carriage base plate. The platen is raised in an oblique direction for the case shift and the segment plate is disposed at the same inclination, thereby limiting the height of the machine and affording space below 25 the carriage for the ribbon shift mechanism, which is preferably mounted on the carriage base plate and is actuated from the rear of the universal bar, the shift mechanism including a link extending forward between 30 the universal bar and the key levers there- below.

Another object of the invention is to provide a universal bar which shall operate in an accurately determined path with a minimum 35 of friction. In the preferred embodiment, the universal bar is suspended from a rocker mounted on the segment plate and an additional link at each side parallel to the rocker arms, to effect a parallel link movement of the universal bar.

Another object is to provide a ribbon-vibrating mechanism including a pivoted lever, one of the arms of which has fingers of different lengths or heights, adjustment means 45 being provided to bring any one of said fingers into the path of operation of the universal bar.

A member is normally interposed between the universal bar and the escapement pawls, 50 through which the thrust from the former is transmitted to the latter.

In the accompanying drawings in which is shown one of various possible embodiments of the several features of this invention,

Fig. 1 is a side elevation partly broken away of the assembled typewriting mechanism,

Fig. 2 is a sectional view taken along the line 2—2 of Fig. 1,

Fig. 3 is a sectional view taken along the line 3—3 of Fig. 1,

Fig. 4 is a fragmentary detail view showing the carriage case shift mechanism at one side of the machine,

Fig. 5 is a fragmentary front elevation of Fig. 1, broken away to disclose the universal-bar control of the ribbon-vibrator.

Similar reference characters refer to similar parts throughout the several views of the drawings.

Referring now to the drawings, I have shown a typewriting mechanism including a base frame 19 provided with a unitary stamped enclosure formed of enclosed side 75 walls 20 and a top 20^a, said enclosure secured to said frame in any well known manner.

Within the base frame are supported the key levers 22, type bars 23, case shift mechanism 24 and other elements to be described below. The base frame includes integral lateral side lugs 25 for supporting thereon a separate or secondary frame structure 37 upon which are carried the ribbon spools 38. The secondary frame 37 includes side standards 39 85 tied together into a unitary structure through having the segment-plate 43 secured at each end to the standards in a suitable manner. Each standard 39 includes an integral lateral spider 40 that assumes a vertical plane to support a horizontal spool-stud 41 provided with a spool-feeding ratchet-wheel 41^a operated by a pawl 41^b reciprocated with the universal bar 42 at each type-bar-actuated movement thereof, to rotate one spool 38 and draw the ribbon across the typing position, as more fully described in my before-mentioned Patent 1,504,199.

As shown in the drawings, the segment plate 43 is disposed relatively low, the central or lowest point of the curved type bar fulcrum wire 57 thereon being substantially

at the level of the upper edges of the bank of key levers 10. The connecting linkage from the key levers to the type bar heels occupies little space otherwise useful, said linkage being disposed largely in the space between the key levers and below the upper edges thereof. The height of the machine is preferably further reduced by inclining the segment plate 43 rearward, in the embodiment shown in the drawings, about 20 degrees, leaving ample space back of the lower or forward part of the segment plate for the escapement and related mechanism, which latter is preferably mounted on the carriage base plate 15 and extends within the boundaries of the universal bar 42, between the segment plate and the rear of the machine.

The typewriter carriage includes the usual base plate 15 having antifriction bearings 16 on which is mounted the platen 17.

The case shift mechanism comprises a pair of spaced-off rods 21 rigid with the typewriter carriage base 15 and extending at right angles to the plane thereof and inclined from vertical, as shown, at an angle of about 20 degrees to extend parallel to the segment plate. The rods 21 are pivoted as at 30 to a pair of the levers 31 rigidly connected together to form a frame rockable about an axis 32 near the rear of the machine, one of said levers having a depression 33 coacting with a tongue 26 at the rear end of the usual shift key lever 27 which is pivoted to one side frame as at 28. The rods 21 are preferably guided in roller bearings 29 to permit elevation of the carriage for case shifting, with a minimum of friction.

The universal bar comprises an arcuate member 42 extending immediately below and assembled to the inclined segment plate 43, which is mounted at an inclination to the vertical, parallel to the case shift rods 21. The universal bar is supported in a special manner to reduce the frictional losses to a minimum and to eliminate inaccuracies resulting from wear. For this purpose, I provide a support bracket 44, Fig. 2, preferably secured as by screws 44' to the segment plate 43 and having a pair of parallel arms 45 and 46 extending rearward and connected by a bar 47. In the preferred embodiment, the suspension comprises a rocker formed of a pair of parallel links 48 and 49, depending respectively from bracket arms 45 and 46 and rigidly connected by a cross bar 50. A pair of separate and distinct links 51 and 52 are pivoted to the rearward or free ends of bracket arms 45 and 46. The universal bar is formed with integral arms 54 and 53 extending rearward from the arcuate segment 42 thereof, and supported respectively from bracket arms 45 and 46 by parallel links 48 and 51 and links 49 and 52. The escapement and associated mechanisms

mounted on the carriage base plate extend into the free space thus provided back of the segment plate and between the universal bar supporting links, as will be more fully described hereinafter. The universal bar, as 70 will be hereinafter described, has separate elements for initiating a plurality of separate and distinct operations of the machine. It will be seen that in operation of the universal bar, the same moves by a parallel link 75 movement, the links advancing and returning by movement parallel to each other. The displacement of the universal bar is by movement strictly parallel to itself without engendering appreciable friction or wear. 80

The pivot pins 70 and 71 for the escapement mechanism are mounted respectively in an angle bar 72 secured to the base plate 15 of the carriage, and a backing bar 73 bolted to said angle bar, and affording a working 85 space 73' therebetween for accommodating said escapement mechanism. The fixed and stepping escapement dogs 74 and 75, respectively, also are disposed between angle bar 72 and backing bar 73, pivots 77 and 78 supporting the fixed dog 74 by ears 76 formed integrally therewith. The stepping dog 75 is pivoted as at 75' upon the fixed dog 74, and a spring 82 connected to the tail of dog 74 urges the stepping dog 75 into cooperation 90 with the escapement wheel 81, while the fixed pawl normally extends in front of said wheel, out of range with the teeth thereof. Spring 74' urges dog 75 to an elevated position limited by tongue 83 on fixed dog 74. 100 The carriage motor (not shown) urges the stepping dog 75 downward against the resistance of spring 74', tongue 83' on said dog limiting said movement by its engagement with the edge of fixed dog 74. The angle 105 and backing bar assembly 72 and 73 is located on the carriage base to the rear of the front end of bracket arms 45 and 46 and of universal bar arms 53 and 54, and projects downward therefrom below the upper end 110 of the universal bar and to the rear of the segment 42 thereof. The escapement dogs 74 and 75 are thus disposed within the space determined by bracket arms 45 and 46 and arms 53 and 54, as will appear clearly from 115 Figs. 2 and 3 of the drawings. The escapement mechanism includes the usual escapement pinion 79 enmeshed with rack 80 on the carriage. The stepping dog 75 is normally in coaction with a tooth of the escapement 120 wheel 81 and the fixed dog 74 is to the front thereof and out of mesh therewith. Upon shift of said dogs as a unit about pivot pins 77 and 78 as an axis, the stepping dog will be released from engagement with an escapement tooth, the expansion of its spring 74' moving it upward about its pivot through the space of one tooth, and the fixed dog enters into engagement with the same tooth, 125 When the universal bar returns to normal 130

- position, the spring 82 vibrates the fixed dog 74 to release the tooth and positions the stepping dog to intercept the next advancing tooth of the wheel, and the carriage spring 5 drum overcomes the resistance of spring 74', and advances the escapement wheel through a distance of one tooth limited by contact of tongue 83' on the dog 75 with the upper edge of the fixed dog 74.
- 10 The escapement wheel 81 is freely mounted upon the support shaft 84, but is connected through spring pawl 85 to the ratchet wheel 86, rotatable as a rigid unit with the pinion 79 upon the common axis of said elements.
- 15 Advance thus takes place by the rotation of pinion 79 through rack 80 and with it of ratchet wheel 86, the latter effecting rotation of the escapement wheel 81 through the pawl 85, as above described.
- 20 The ribbon-vibrating mechanism is preferably mounted on the carriage base plate rather than on the frame. The ribbon 104 is held in the usual ribbon-carrier 103 and adjacent the platen and below the typing line thereon. The vibration of the ribbon for raising it to printing position is effected through a linkage attached to the shifttable carriage base plate in the path of movement of the universal bar and extending, as indicated in the drawings, under the universal bar between the latter and the key levers, so that the mechanism does not add materially to the over-all height of the machine. The linkage comprises a rocker 105 having integral ears 106 pivoted as at 107 in yoke bracket 108, the latter secured to the rear of the backing bar 73, which is secured on the carriage base plate as heretofore described. Integral with rocker 105 is a ribbon-vibrating arm 109 extending forward therefrom and terminating adjacent the segment plate 43 to pivotally support the ribbon-carrier 103 at its free end. The rocker 105 may be provided with an arm extending upward therefrom into the path of a nose 111 projecting at the rear of a bridge member 134 which latter may be riveted as at 135 to the ends of the arcuate universal bar 42. Although this lever arm may be formed with a fixed point to be engaged by the nose 111 in order to raise the ribbon through a fixed range at each operation, I have shown an arrangement providing for two alternative degrees of elevation of the ribbon and particularly useful for a two-color ribbon shift mechanism, and affording a third setting out of the path of operation of the universal bar for stencil writing. In the preferred embodiment shown, the rocker 105 has mounted thereon a shift plate 112 provided with an elongated slot 113 secured to the rocker 105 by screws 114 extending through the slot 113 and threaded into said rocker 105. The shift plate 112 carries a pair of integral up-standing tongues 115 and 116 of different heights, having forwardly projecting ends 117, either of which tongue ends may be brought into the path of the long nose 111 of the universal bar by corresponding shift of the plate 112 along the screws 114.
- 70 A spring 119 secured to the rocker 105 forms a detent to snap into any one of three notches 121', 121² and 121³ in the shift plate 112, for accurately positioning the same in any setting, the central of said notches corresponding to stencil setting in which both tongues 115 and 116 are maintained out of the path of the nose 111 of the universal bar and the ribbon is not vibrated. Notches 121' and 121³ correspond to the two operative or ribbon vibrating settings, in which tongues 115 and 116 respectively are in the path of said nose 111 of the universal bar. Stops 123 and 124 are provided upon yoke bracket 108 for limiting the displacement of the tongues 115 and 116 respectively, and these stops may be set screws, as shown.
- 75 In the preferred embodiment, the usual shift lever (not shown) may be employed to set the shift plate 112 and the two tongues 115 and 116 relatively to the nose 111 through connecting parts including a link 166 (Fig. 5).
- 80 It will be seen that the ribbon vibrating linkage affords substantial multiplication of ribbon displacing motion predetermined by the height of the tongues 115 and 116 actuated by the universal bar. Therefore, the elevation of the ribbon will be substantially greater than the shift of the universal bar. The ribbon vibrating mechanism, however, does not add substantially to the bulk of the machine, since the linkage is fitted into spaces otherwise unoccupied below the platen to the rear of the universal bar and between the latter and above the key levers.
- 85 90 95 100 105 110 115 120 125 130
- It will be readily understood that when the longer tongue 115 is shifted to lie in the path of nose 111 of the universal bar, the ribbon-vibrating arm 109 will be shifted by the operation of the universal bar through a lesser range about its pivot 107 than when the shorter tongue 116 is presented to said nose.
- More particularly in foreign languages, there is occasion to type certain auxiliary marks, such as accents, umlauts and cedillas, in the same space with the usual letters. With the ordinary typewriter, it is necessary after printing a letter to operate the back space key in order to re-align for then printing the auxiliary character in the same space. According to my invention, I arrange certain keys that correspond to the auxiliary marks to effect the regular universal bar operation, but to cut out the operation of the escapement.
- For this purpose, the thrust from the universal bar to the escapement dogs 74 and 75 may be transmitted through an interposed

or intermediary piece 125 normally maintained in place but automatically removed while one of the said non-escapement keys is depressed, so that the universal bar will operate all of the control mechanism in the normal fashion with the exception only of the escapement mechanism.

In the preferred specific embodiment, the universal bar bridge member 134 is provided with an escapement operating tongue 126 cooperative with a long lever 127 pivoted as at 128 near one side of the machine and formed with a tongue 129, the end of which constitutes the interponent 125, normally maintained interposed between the tongue 126 on the universal bar and the escapement dog 74, so that in normal operation, the thrust is transmitted therethrough to the escapement dogs from the tongue 126 on the universal bar. The said non-escapement keys are preferably connected to lever 127 by links such as 130 and 131 fitting in corresponding notches 132 in the lever, so that upon depression of any of said keys, the lever 127 will be depressed about its pivot against the resistance of spring 133 to remove piece 125 from between the universal bar tongue 126 and the dog 74, so that in the continued movement of the key as the printing occurs and the universal bar is shifted, the shift of tongue 126 on the latter will take place in the gap left in advance thereof by the removal of the interposed element 125, wherefore the escapement dog 75 will not be vibrated and the carriage will not be advanced.

What I claim as new and desire to secure by Letters Patent is:—

1. In a portable typewriting machine, the combination with a carriage having an escapement mechanism, and a segment supporting a series of type-bars, of means actuated by all the type-bars and operatively connectible to the escapement mechanism to letter-space the carriage, said means including a curved universal bar having a pair of rearwardly-projecting widely-spaced tongues, a pair of links pivotally-supporting each tongue, and a pair of brackets vertically aligned to said tongues and secured to the rear of the segment to support the links, the brackets, links and tongues jointly forming side walls of an open space within which the escapement mechanism is positioned close to the segment for a condensed assembly of the parts.

2. In a typewriting machine, the combination with a carriage having an escapement mechanism shiftable therewith to case-shift position and a series of type-bars assembled upon a stationary segment, of means mounted upon the segment to be actuated by the type-bars and connectible to the escapement mechanism at either case-shift position thereof, said means including a curved member engageable by the type-bars, and a bridge-

member secured to the ends of the curved member, said bridge-member having connections to convey the movement of the type-bar-actuated curved member to the same part of the escapement mechanism, at either case-shift position of the carriage.

3. In a typewriting machine, the combination with a carriage having an escapement mechanism shiftable therewith to case-shift position and a series of type-bars assembled upon a stationary segment, of a universal mechanism swingably mounted upon the stationary segment to be actuated by the type-bars and inoperative to actuate the escapement mechanism, said universal mechanism including a curved member engageable by the type-bars and a bridge-member secured to the ends of the curved member, said bridge-member having a tongue projecting towards the escapement mechanism, and an intermediary member engageable by said tongue and operative to uniformly vibrate the same part of the escapement mechanism at either case-shift position thereof when a type-bar is actuated.

4. In a typewriting machine, the combination with a carriage having a carriage-feeding mechanism and a series of type-bars assembled upon a segment, of means swingably mounted at the rear of the segment and poised between the type-bars and the escapement mechanism, said means including a curved universal bar operative by the type-bars, and a cross-bar to bridge the ends of the curved bar, said cross-bar having a tongue operative to engage the carriage-feeding mechanism at each actuation of the universal bar by a type-bar.

5. In a typewriting machine including a carriage having a platen, a ribbon-carrier operative to present a ribbon to the typing line of the platen, a carriage-escapement mechanism, and a series of type-bars assembled upon a segment, the combination of means swingably mounted upon the segment to be operated by the type-bars and operative to actuate the carriage-escapement mechanism and vibrate the ribbon-carrier to cover the typing position upon the platen, said means including a curved universal bar engageable by the type-bars, and a bridge-member secured to the universal bar, said bridge-member including a tongue operative to vibrate the escapement mechanism, and an extension operative to vibrate the ribbon-carrier at each actuation of the universal bar by a type-bar.

6. In a typewriting machine including a carriage having a platen, a ribbon-carrier operative to present the ribbon to the typing position on the platen, ribbon-spools operative to feed the ribbon through the ribbon-carrier, a carriage-escapement mechanism, and a series of type-bars assembled upon a segment, the combination of means

- swingably mounted upon the segment to be operated by the type-bars and operative to jointly actuate the carriage-escapement and vibrate the ribbon-carrier to the printing position and rotate a ribbon-spool to feed the ribbon, said means including a curved universal bar operable by the type-bars and a cross-bar to bridge the ends of the universal bar, said cross-bar at each end having connections operable to feed a ribbon-spool, a tongue adjacent the center thereof operable to engage the carriage-escapement to feed the carriage, and an extension operative to vibrate the ribbon-carrier at each actuation of a type-bar.
7. In a portable typewriting machine, the combination with a base-frame having a segment-plate secured thereto for pivotally supporting a series of type-bars and a case-shifting frame to support a platen-carriage and an escapement-mechanism for the carriage, of a universal bar curved about the stationary segment-plate to be operated by the type-bars and formed with extensions that project rearwardly at each side of the escapement-mechanism to provide a working clearance space between them for the rise and fall of said escapement-mechanism in case-shifting, and means for pivotally securing said universal bar as a unit to the rear of the stationary segment-plate for a swinging parallel motion between the type-bars and the escapement-mechanism to uniformly actuate the latter at any case-shift position thereof.
8. In a portable typewriting machine, the combination with a base-frame having a segment-plate secured thereto for pivotally supporting a series of type-bars and a case-shifting frame to support a platen-carriage and an escapement-mechanism for the carriage, of a universal bar curved about the stationary segment-plate to be operated by the type-bars and formed with extensions that project rearwardly at each side of the escapement-mechanism to provide a working clearance space between them for the rise and fall of said escapement-mechanism in case-shifting, means for pivotally securing said universal bar as a unit to the rear of the stationary segment-plate for a swinging parallel motion between the type-bars and the escapement-mechanism, and an ear integral with the universal bar and having a one-way connection operative to uniformly vibrate the escapement-mechanism at any case-shift position thereof.
9. In a portable typewriting machine, the combination with a base-frame having a segment-plate secured thereto for pivotally supporting a series of type-bars and a case-shifting frame to support a platen-carriage and an escapement-mechanism for the carriage, of a universal bar curved about the stationary segment-plate to be operated by
- the type-bars and formed with extensions that project rearwardly at each side of the escapement-mechanism to provide a working clearance space between them for the rise and fall of said escapement-mechanism in case-shifting, means for pivotally securing said universal bar as a unit to the rear of the stationary segment-plate for a swinging parallel motion between the type-bars and the escapement-mechanism, an ear integral with the universal bar and movable therewith towards the escapement-mechanism and within a clearance-space between said ear and said mechanism, and an intermediary member interposable between said ear and escapement-mechanism to fill up said clearance-space and render said ear operable to vibrate said escapement-mechanism uniformly at any case-shift position thereof.
10. In a portable typewriting machine, the combination with a carriage having a carriage-feeding mechanism and a series of type-bars assembled upon a segment, of a universal bar curved about said segment and wholly supported by means projecting from the rear of the segment for a floating parallel motion thereof between the type-bars and the carriage-feeding mechanism to actuate the latter, said supporting means including a pair of widely separated brackets secured to the rear face of the segment, a pair of links pendent from each bracket, and a pair of arms integral with the universal bar that are aligned to the brackets and secured to the free ends of the links.
11. In a portable typewriting machine, the combination with a base-frame having a segment-plate fixed thereto for supporting a series of type-bars, and a case-shift frame shiftably mounted upon said base-frame and supporting a platen-carriage and an escapement-mechanism therefor, of a universal bar curved around said segment-plate and pivotally mounted at the rear thereof for a swinging parallel motion when actuated by the type-bars, said universal bar including an open frame-work to afford a working clearance-space for the case-shifting movement of the escapement-mechanism positioned close to the rear of the segment for a compact assembly of the parts and also provide long bearing supports for the universal bar at each side of the escapement-mechanism.
12. In a portable typewriting machine, the combination with a series of type-bars assembled around a segment and a carriage having a letter-spacing mechanism therefor, of a universal-bar unit poised at the rear of the segment upon widely separated side bearings that form a pocket, within which pocket the letter-spacing mechanism is compactly assembled to economize in space, said unit including a bar curved about the segment to be engaged by the type-

bars, spaced-off side arms projecting rearwardly therefrom to enclose the letter-spacing mechanism upon two sides, brackets aligned to each side arm and secured to the rear of the segment, and a pair of parallel links pivotally connecting each bracket and side arm to suspend the universal bar as a

unit between the type-bars and the letter-spacing mechanism.

Signed at New York city, in the county 10 of New York and State of New York, this 10th day of July, A. D. 1924.

LOUIS A. NEMCOVSKY.
